UNITED STATES PATENT OFFICE.

GEORGE M. GRAHAM, OF CHICAGO, ILLINOIS, ASSIGNOR TO G. A. EDWARD KOMLER, OF CHICAGO, ILLINOIS.

REINFORCED CONCRETE STEP.

No. 867,818.

Specification of Letters Patent.

Patented Oct. 8, 1907.

Application filed June 1, 1907. Serial No. 376,809.

To all whom it may concern:

Be it known that I, GEORGE M. GRAHAM, a citizen of the United States of America, and a resident of Chicago, in the county of Cook and State of Illinois, have invented certain new and useful Improvements in Reinforced Concrete Steps, of which the following is a specification.

This invention relates to reinforced concrete steps for buildings, and has for its object to provide a simple and efficient structural arrangement and combinations of parts whereby a very strong and economical step structure is provided, all as will hereinafter more fully appear.

In the accompanying drawings:—Figure 1, is a vertical section of a portion of a flight of stairs embodying the present invention. Fig. 2, is a fragmentary plan view of one side of the metal reinforce frame upon which the concrete mass is supported. Fig. 3, is a detail section on line x—x Fig. 1.

Similar numerals of reference indicate like parts in the different views.

Referring to the drawings, 1 represents the side stringers of the stairway which in the present invention are preferably formed of structural metal such as channel bars, and having the usual inclined arrangement, as shown.

2 are a series of round cross rails extending between the stringers 1 aforesaid, and having a zig-zag arrangement, with each cross rail in a vertical and a horizontal plane, respectively, with the next adjacent cross rails, as illustrated in Fig. 1.

3, are windings of wire wound in the circuitous manner shown around the cross rails 2, so as to form skeleton supports for the mass of concrete 4, which when applied thereto forms the treads and risers of the stairs as shown, and adapted to afford a fire proof structure of great strength and stability.

In the preferred form of the present invention, each cross rail 2, consists of an outer tube 5, and an inner tube

6, with the outer tube having abutment against the inner faces of the stringers 1, while the respective ends of the inner tube pass through orifices formed therefor in the stringers 1 and are upset against the outer faces of such stringers, as shown in Fig. 3, to afford a very strong and durable connection of the parts.

Having thus fully described my said invention, what I claim as new and desire to secure by Letters Patent, is:

1. Reinforced concrete steps, comprising side stringers, a series of cross rails extending between said stringers and arranged in zig-zag relation, windings of wire connecting said rails, and a mass of concrete inclosing said rails and windings to form the treads and risers of the steps, substantially as set forth. 50

2. Reinforced concrete steps, comprising side stringers, a series of cross rails formed of round tubing and extending between said stringers and arranged in zig-zag relation, windings of wire connecting said rails and a mass of concrete inclosing said rails and windings to form the treads and risers of the steps, substantially as set forth. 55

3. Reinforced concrete steps, comprising side stringers, a series of cross rails formed of round tubing and extending between said stringers and arranged in zig-zag relation, members arranged within said tubular cross rails and extending through the stringers and upset against the outer faces thereof, windings of wire connecting said rails, and a mass of concrete inclosing said rails and windings to form the treads and risers of the steps, substantially as set forth. 60

4. Reinforced concrete steps, comprising side stringers, a series of cross rails formed of round tubing and extending between said stringers and arranged in zig-zag relation, tubular members arranged within said tubular cross rails and extending through the stringers and upset against the outer faces thereof, windings of wire connecting said rails, and a mass of concrete inclosing said rails and windings to form the treads and risers of the steps, substantially as set forth. 70

Signed at Chicago, Illinois this 23rd day of May 1907.

GEORGE M. GRAHAM.
